UNITED STATES PATENT OFFICE.

JAMES H. LUTHER, OF OLEAN, NEW YORK.

HOSE-REEL ATTACHMENT.

SPECIFICATION forming part of Letters Patent No. 427,334, dated May 6, 1890.

Application filed September 17, 1888. Renewed March 29, 1890. Serial No. 345,870. (No model.)

To all whom it may concern:

Be it known that I, JAMES H. LUTHER, a citizen of the United States, residing at Olean, in the county of Cattaraugus and State of New York, have invented certain new and useful Improvements in Hose-Reel Attachments; and I do declare the following to be a full, clear, and exact description of the invention, such as will enable others skilled in the art to which it appertains to make and use the same, reference being had to the accompanying drawing, and to the letters of reference marked thereon, which form a part of this specification.

15 The figure represents a vertical transverse section of the device.

This invention relates to improvements in hose-reels of that class where the reels are placed permanently in close proximity to a water-supply, so that when the hose is run off the water may be quickly turned on simultaneously with the unreeling of the hose.

The invention consists in the construction hereinafter pointed out.

25 In the annexed drawing, the letter A indicates any ordinary water-supply pipe. This pipe has a T-joint a, with a valve-seat a' at its outlet. This T is used where there are several attachments to the pipe. If there is one only, the opening a² of the T is closed. This T has the usual water-ways a³ and a relief-passage a⁴. Secured to this T is the box B, provided with an enlarged chamber b' and the threaded opening b². Engaging this opening b² is a section of pipe C, the top of which is held to another section D by a flange-union c. This section D has a collar d, and its upper end is closed. Resting upon this collar d is a spider E, the collar d entering a recess e on the under side of the spider, and a gland F, surrounding section D, holding the spider

on and packing it. Around the perforated end of the section D this spider E has a chamber G, and projecting from the spider are the radial sockets e', carrying the spokes H. The 45 spider E also has a threaded opening k, in which is screwed a pipe K, having the bent threaded end K'. On top of these arms and the pipe is placed a drum L, the latter having notches l to hold it firmly in place. The top 50 of the spider E has a hole through which projects the valve-stem P, and where it is secured by a pin p, thus locking the reel and valve-stem securely together. The valve-stem passes down the water-pipe through the box B and 55 is fastened to the valve p' at the bottom. The reel and valve-stem being thus rigidly held together, as the reel is unwound the valve is opened. To close the valve the reel is wound up. 60

This invention relates to the same class as that contained in another application filed September 17, 1888, and has features common to both devices, and which are not detailed here. 65

What I claim is—

The combination of the water-supply pipe having the perforated end and the valve within the pipe and the valve-stem projecting out of the pipe with the hose-reel having a chambered spider around the perforated end of the water-supply pipe, the projecting end of the valve-stem being secured to this spider, whereby the rotation of the reel operates the valve-stem to open or close the valve, as set 75 forth.

In testimony whereof I affix my signature in presence of two witnesses.

JAMES H. LUTHER.
